UNITED STATES PATENT OFFICE.

GEORGE FRANCIS BELL, OF TULSA, OKLAHOMA.

FLANGE FOR BULL-WHEEL SHAFTS.

Application filed October 22, 1923. Serial No. 670,065.

To all whom it may concern:

Be it known that GEORGE F. BELL, a citizen of the United States, residing at Tulsa, in the county of Tulsa and State of Oklahoma, has invented certain new and useful Improvements in Flanges for Bull-Wheel Shafts, of which the following is a specification.

This invention relates to a novel construction of flanges such as are utilized in connection with bull wheel shafts of oil well drilling machinery for guiding and retaining in desired position a cable through which the drilling tools are manipulated.

Heretofore flanges of the type in question have been constructed in such a manner that the cable in certain positions is bent or kinked by engagement with the bolts which retain the flange sections together on the shaft. Obviously a cable bent as indicated will necessarily be out of alignment and quickly wear by contact with the casing with the result that the cable portion so injured must be discarded resulting not only in unnecessary expense but in a waste of time and labor.

By the present invention I have constructed a flange which will at all times keep the cable free from engagement with the bolts and will permit the desired movement of the cable, the flange itself being of unusual strength and durability.

More specifically I have provided a sectional metal flange with a guideway for carrying the cable direct from the shaft to either the reserve or working coil, such guideway being formed substantially as an integral element of one of the flange sections and comprising an arc-shaped groove section adjacent the upper edge of the upper section and extending diagonally of the transverse axis of the shaft on which it is mounted, to opposite sides of said flange, and two vertical guideways which merge at their upper ends into the terminals of said arc-shaped groove and at their lower ends into tapered guides formed by inclined wall portions of the hub of the lower flange section.

Also I have included liners to permit the use of the present invention on either wooden or steel shafts, these liners being shaped to conform to the shape of the flange hub portions and to co-operate with the cable guideway.

Other features of construction and advan-

tages derived from the present arrangement will more clearly hereinafter appear by reference to the accompanying drawings forming a part of this specification and wherein like numerals of reference designate corresponding parts throughout the several views, in which:

Figure 1 is a side elevation showing the flange in position on the bull wheel shaft. 65

Figure 2 is a similar view enlarged showing only a portion of the shaft.

Figure 3 is a top plan view showing the flange in position.

Figure 4 is a front elevation. 70

Figure 5 is a plan view of the lower half of the flange.

Figure 6 is a plan view showing the section of liner used in the upper half of flange, and 75

Figure 7 is a similar view of the lower flange section.

The present invention is shown arranged on the bull wheel shaft A which may be of either wood or steel as will more clearly appear, and comprises upper flange section B and lower section C. Both of these sections are of cast metal and are provided with hub sections b and c and radiating semi-circular flange portions b' and c' respectively. A series of webs D are utilized to strengthen the flange portions b' and c' and to effect a fixed relationship between such flange portions and the hub portions b and c. These reinforcing webs are arranged in such a manner 90 as to secure the best possible strength of the entire unit and it will be seen from an examination of the drawing that various short web portions connect the elements of the upper and lower flanges. Suitable bolts E secure the flange sections B and C together and extend through tubular enlarged portions e provided therefor on opposite sides of the hubs. 95

Referring now to the substance of the present idea attention is first directed to the path of travel of the cable a illustrated more clearly in Figures 2 and 3. From these figures it will be seen that the cable a is carried to the opposite sides of the flange for 100 its different functions by means of novel guideways or grooves. These guideways include in the upper section B the arc-shaped section F having a radius substantially identical with the radius of the shaft A but with 105 an axis spaced above the circumference of the latter, and the vertical parallel guide-

ways f and f' . These guideways f and f' are formed in the opposite faces of the flange section B and merge into the arc-shaped groove F which latter necessarily extends diagonally to the transverse axis of the shaft A. An examination of these grooves or guide-ways will disclose wall sections which partially enclose same to assist in retaining the cable in the desired path of travel.

At opposite ends and on opposite sides g and g' the hub portion c of the lower flange section C is cut away at such angles as may be necessary to permit access of the cable a to the vertical guideways f and f' and proper feeding of such cable to the shaft A.

In Figures 6 and 7 I have illustrated liners H and J. These liners are necessary in instances where a steel bull wheel and shaft is used inasmuch as such steel shafts measure 16" outer diameter to 18" outer diameter of the wooden shafts. Suitable keys and retaining lugs are provided to fix these liners in position.

The liner H for the upper hub section B has cut away portions at diametrically opposite points h and h' where the vertical guideways f and f' terminate and the lower liner J is necessarily cut away at j and j' to correspond to the contour of the hub portion to which it is applied.

The application and use of the present invention will be apparent to one skilled in the art. The particular construction and arrangement of the guide grooves providing for the feeding and manipulation of the cable to opposite sides of the flange as may be desired, the cable being at all times free from binding or crimping due to engagement with irregular surfaces.

What I claim as new and useful and desire to secure by Letters Patent, is—

1. In combination, a shaft, a cable to be coiled on said shaft and a flange mounted on the shaft and formed with a guideway for said cable, said guideway extending from one side of said flange to the other and terminating at points adjacent said shaft.

2. A flange for a bull wheel shaft including upper and lower sections, one of said sections being formed with an arc-shaped groove communicating with opposite sides of said flange, and a guideway communicating with said groove at each end thereof, each of said guideways terminating at a point adjacent said shaft.

3. A flange for a bull wheel shaft including upper and lower sections, means for

securing said sections together, and an arc-shaped groove in said flange spaced between said securing means communicating with opposite sides of said flange, said groove terminating at diametrically opposite points on said shaft.

4. In a device of the class described including in combination a shaft, a cable, a flange and guide means for said cable formed integral with said flange and including a curved groove formed in one side of said flange and extending from one side of said flange to the other and guideways arranged on opposite faces of said flange and communicating with said curved groove.

5. A flange for a bull wheel including upper and lower sections and a hub, a groove formed adjacent the upper periphery of said upper section and extending from one side of said section to the other, and grooves formed in the opposite faces of said upper section communicating with the first mentioned groove and terminating adjacent said hub, and guide walls formed at opposite sides of said hub and communicating with said grooves.

6. In a device of the class described including in combination, a shaft, a cable on said shaft, a flange for said shaft including upper and lower sections and a hub portion, a curved groove formed adjacent the upper periphery of said upper section and arranged diagonally to the transverse axis of said shaft to communicate with the opposite faces of flange section, a vertical parallel guide way formed in each of the opposite faces of said upper flange section and merging into said curved groove at their upper ends, the lower ends of said vertical guideways terminating at points adjacent said shaft, and walls formed in the hub portion of the lower flange section to guide said cable to said vertical guide ways.

7. In a device of the class described including in combination, a shaft, a cable, and a guide flange mounted on said shaft formed with a transverse cable guideway extending from a point adjacent said shaft on one side of said flange to a point adjacent said shaft on the opposite side of said flange.

8. In a device of the class described, a shaft, a cable, and a flange mounted on said shaft having cable guideways in its opposite faces extending from a point adjacent said shaft and communicating with a connecting curved groove formed at a point spaced from the outer face of said shaft.

In testimony whereof I affix my signature.
GEORGE FRANCIS BELL.
